UNITED STATES PATENT OFFICE

132,735

DESIGN FOR A MATCH FOLDER

Russell R. Isenhour, Geneva, N. Y., assignor of one-half to Valere L. Minet, Geneva, N. Y.

Application January 2, 1942, Serial No 104,979

Term of patent 14 years

To all whom it may concern:

Be it known that I, Russell R. Isenhour, a citizen of the United States, residing at Geneva, in the county of Ontario and State of New York, have invented a new, original, and ornamental Design for a Match Folder, of which the following is a specification, reference being had to the accompanying drawing, forming part thereof.

In the aforesaid drawing:

Figure 1 is a front elevational view of a match folder showing my new design; and Figure 2 is a side elevational view thereof.

I claim:

The ornamental design for a match folder, as shown.

RUSSELL R. ISENHOUR.
